DESIGN FOR A LIGHTING FIXTURE

Davis H. Tuck, Norwalk, Conn., assignor to Holophane Company, Inc., New York, N. Y., a corporation of Delaware

Application April 19, 1933. Serial No. 47,833

Term of patent 7 years

To all whom it may concern:

Be it known that I, DAVIS H. TUCK, a citizen of the United States of America, and a resident of Norwalk, in the county of Fairfield and State of Connecticut, have invented a new, original,
and ornamental Design for a Lighting Fixture, of which the following is a specification, reference being had to the accompanying drawing, forming a part thereof. In the drawing:

Fig. 1 is an elevation of my design,

Fig. 2 is a perspective of my design with the lower portion cut away.

I claim:

The ornamental design for a lighting fixture
as shown and described.

DAVIS H. TUCK.
